[57] CLAIM

The ornamental design for a vehicle light cover, as shown and described.

DESCRIPTION

FIG. 1 is a front view of a vechile light cover according to our novel design;

FIG. 2 is a left view of the vehicle light cover according to our novel design; and,

FIG. 3 is a right view of the vehicle light cover according to our novel design.

The dash lines shown depict environmnet and are not part of the claimed design.

This design represents one embodiment of a vehicle light cover. The depicted embodiment is the left side light cover. The design also contemplates a right side embodiment that is mirror symmetrical to the design illustrated and is therefore not separately illustrated.
